ALPHABETICAL AND NUMERICAL CHARACTER

Charles A. Dinlocke and Alois E. Steiert,
Philadelphia, Pa.Substituted for abandoned application Serial No.
405,118, August 1, 1941. This application No-
vember 30, 1949, Serial No. 130,212

3-Claims. (Cl. 40—136)

1

Our invention relates to a new and useful alphabetical and numerical character and especially such characters made of foldable paper and other suitable thin sheet material for use as elements of a sign. This application is a substitute for abandoned application Serial No. 405,118 filed August 1, 1941.

An object of the invention is to provide an exceedingly simple, inexpensive and effective character of this kind having three dimensions, namely, height, width and depth.

Another object of this invention is to produce a character of the kind mentioned in which the sides that give depth to the character are of angular formation so as to be readily adaptable to characters of different configurations.

A further object of the present invention is to provide a character that may be formed from a blank cut out by a die used in an automatic or non-automatic cutting and scoring or folding machine so that said blanks can be produced inexpensively.

A still further object of the invention is to provide means for reinforcing the characters and the reinforcing means may include or carry means for suspending the characters on a support or background.

With the above and other objects in view this invention consists of certain details of construction and combination of elements to be herein after set forth and then designated by the claims.

In order that those skilled in the art to which this invention appertains may understand how to make and use the same, we will describe the construction of certain characters in detail, referring by numerals to the accompanying drawing, in which:

Fig. 1 is a front elevation of one character illustrating the invention.

Fig. 2 is a rear elevation thereof.

Fig. 3 is a plan view of one of the blanks used in producing the character illustrated in Fig. 1.

Fig. 3A is a similar view of the other blank used in forming the character shown in Fig. 1.

Fig. 4 is a plan or face view of the reinforcing member for the same character.

Fig. 5 is a section on the line 5—5 of Fig. 1.

Fig. 6 is a section on the line 6—6 of Fig. 1.

Fig. 7 is a perspective view of a portion of the reinforcing member with one of the tabs protracted.

Fig. 8 is a front elevation of another character illustrating the invention.

Fig. 9 is a rear elevation of Fig. 8.

Fig. 10 is a plan view of the single blank used

2

for producing the character illustrated in Fig. 8.

Fig. 11 is a section on the line 11—11 of Fig. 8.

In carrying out our invention as herein embodied, particular reference being first had to Figs. 1 to 7 inclusive, 15 represents the main or primary blank for producing plain angular characters but in the case of such letters as "E," "F" and the like an additional blank, to be later described, is required.

10 The blank 15 consists of a sheet of paper fashioned to provide a body 16 with legs 17 projecting at suitable angles from the ends of said body. The body and legs are positively defined by the oblique transverse fold lines 18.

The body 16 and legs 17 are provided with longitudinal fold or score lines 19, 20 and 21 to define side wall areas 22 and edge flange areas 23 and the flange areas of the legs are separated from the flange areas of the body.

15 Also the outer end of each leg has a slit 24 extending from adjacent one side of the outer end of the leg to the central fold line 20 of the same leg oblique to said fold line and from the inner end of said slit extends an oblique fold line 25 to the outer end of a side fold line, as 19, and between said slit 24 and the fold line 25 extends another fold line 26 thus defining a triangular area 27 and a tab 28. Further a fold line 29 extends from the inner end of the slit 24 to the outer end of the other longitudinal side fold line 21 of the leg and from the point of meeting of the fold lines 21 and 29 to the slit 24 extends a fold line 30 defining a second but smaller triangular area 31 and a tab 32.

20 The secondary blank 33 also consists of paper fashioned to provide a separate leg 34 which is provided with longitudinal fold or score lines 35, 36 and 37 to define side wall areas 38 and edge flange areas 39. Similar to the legs 17, this separate leg has a slit 40 extending from adjacent one side of the outer end of said separate leg to the central fold line 36 oblique to said fold line 36 and from the inner end of said slit extends an oblique fold line 41 to the outer end of a side

25 fold line, as 37, and between said slit 40 and the fold line 41 extends another fold line 42 defining a triangular area 43 and a tab 44. Also a fold line 45 extends from the inner end of the slit 40 to the outer end of the other longitudinal side fold line, as 35, of said separate leg and from the point of meeting of the fold lines 35 and 45 to the slit 40 extends a fold line 46 defining a triangular area 47 and a tab 48. Further the inner end of the blank, constituting the separate leg 34, is provided with oblique fold lines 49 and 50 ex-

tending from the side fold lines 35 and 37 respectively to the central fold line 36 defining attaching tabs 51 from the side wall areas 38.

In forming the character 52, herein shown as the letter "E," from the above described blanks, the primary blank 15 is folded on the medial fold lines 20 to provide the oppositely inclined side walls 22' and this folding of the blank draws in the leg portions 17 by the creation of an inside corner 18' and an outside corner 18". The flange areas 23 are turned in to provide attaching elements 23', Figs. 2 and 6, which may be wide enough to overlap one another or fastened by an intervening web or attached to a support. Similarly the triangular areas 27 and 30 of each leg 17 are folded towards each other on the fold lines 25 and 29 and the larger area 27 is positioned on the outside of the smaller area 30 to form an inclined end wall 27' and the tabs 28 and 31 are turned in so that the tab 28 provides an attaching element 28', Fig. 2, for the same purpose as specified for the first mentioned attaching elements. The overlapping triangular areas 27 and 31 as well as the overlapping flaps 28 and 32 may be fastened together, as by an adhesive.

Likewise the secondary blank 33 is folded or bent along the medial fold line 36 to provide the inclined side walls 38', the same as the side walls 22', and the flange areas 39 are turned in to form attaching elements 39' and also the triangular areas 43 and 47 are folded towards each other so that the larger area 43 overlaps the smaller area 47 to provide the inclined end wall 43'. The tabs 44 and 48 are bent in to form an attaching element 44'.

The inner end of the secondary blank is folded along the fold lines 41 to provide the flaring inclined edges 49', Fig. 3A, which fit the inclination of the walls 22' and the attaching tabs 51 which may be secured to the outer face of said side walls 22' within the boundaries of the side walls 38', which fit the inclination of the walls 22' and the attaching tabs 51 which may be secured to the outer face of said side walls 22' within the boundaries of the side walls 38', as by an adhesive, to complete the character.

The character thus produced may be stiffened and strengthened by securing it to a reinforcing member 53 composed of cardboard and fashioned to the outline of the particular character with which it is to be used. The paper character is fastened to reinforcing member 53 by the attaching elements and to provide for the center limb of the reinforcing member the flange area 23 at the inner side of the primary blank is slit transversely at two points indicated by the numeral 54 to partially sever the material between the locations of the slits which material is then turned in to lie above the reinforcing member as shown by dotted lines at 55 in Fig. 1, although said material can be completely removed.

This reinforcing member may carry suspending means, and a convenient manner of providing such suspending means is to partially cut out areas of the reinforcing member to form tabs 56 which can be bent outward on the fold lines 57 as shown in Fig. 7. These suspending means or tabs may be inserted in slots in a support or background to temporarily hold the character in place and said suspending means may be bent over onto the reverse face of the support to prevent accidental displacement of the character.

Referring now to Figs. 8 to 11, inclusive, we have illustrated a different character, particular-

ly the letter "R," completely formed from a single blank and including a curved portion as well as the straight portions.

In this, the blank 58 is fashioned to provide a stem 59, a curved branch 60 and a tail 61. All of the above mentioned parts are defined by transverse fold lines 62, between the stem and curved branch, and 63, between the curved branch and tail.

The stem, curved branch and tail are provided with longitudinal fold or score lines 64, 65 and 66 parallel with the straight edges and concentric with the curved edges to define side wall areas 67 and side flange areas 68. The side flange areas of each part of the blank are separated from one another and said side flange areas in the region of the curved portion or branch are slit radially to provide a multiplicity of serrations 69.

The outer or free ends of the stem 58 and the tail 61 are formed the same as the outer ends of the legs in the first described character and the same reference numerals will be used; therefore, a slit 24 extends from adjacent one side of the outer end of the members, namely, the stem and the tail, to the medial fold line 65 oblique to said fold line. From the inner end of said slit extends an oblique fold line 25 to the outer end of a side fold line, and between said slit 24 and the aforementioned fold line extends another fold line 26 thus defining a triangular area 27 and a tab 28. Further a fold line 29 extends from the inner end of the slit 24 to the outer end of the other side fold line and from the point of meeting of the fold lines 21 and 29 to the slit 24 extends a fold line 30 defining a smaller triangular area 31 and a tab 32.

In forming the character 70, herein shown as the letter "R," from the last described blank 58, said blank is folded on the medial fold lines 65 to provide the oppositely inclined side walls 59' and this folding of the blank shortens the curve of the branch 60 and draws the tail 61 towards the stem 59 by the creation of the inside corner 62' and the outside corner 62" along the fold line 62 and a similar inside corner 63' and outside corner 63" along the fold line 63 to give proper shape to the character 70 illustrated in Fig. 8.

The flange areas 68 are turned in to provide attaching elements 68', Figs. 9 and 11, and it will be noted that the serrated portions when on the inside of a curve spread out but when on the outside a curve close up and overlap one another. The attaching elements may be utilized the same as previously set forth with relation to the first described character. The triangular areas 27 and 31 which form the inclined end wall 27' at the terminal of any part of the character and the associated tabs 28 and 32 which provide the attaching element 28' are identical in construction with the similarly numbered ones first described.

The character 70 may be stiffened and strengthened by a reinforcing member 71 which, like any other, must have the outlines or shape of the character to be attached thereto. The reinforcing member may carry suspending tabs 72 and for convenience and cheapness these tabs may be formed by partially cutting out areas of the reinforcing member and bending them along the fold lines 73.

While we have shown and described only the construction of the letters "E" and "R" it is to be understood that the character may be any letter of the alphabet or any numeral since they

are composed of either straight or curved parts or combinations thereof and the illustrated characters disclose both kinds of formations.

Of course we do not wish to be limited to the exact details of construction as these may be varied within the limits of the appended claims without departing from the spirit of our invention.

Having described our invention what we claim as new and useful is:

1. A character of the kind described comprising a blank of paper fashioned to a shape that when folded will result in a predetermined configuration and having three longitudinal parallel fold lines defining joined side walls which assume inclined positions and side flanges that project inwardly to function as attaching elements, each free end having an oblique slit extending from adjacent one side of the extreme outer end to the medial fold line and also having fold lines extending obliquely from the inner end of the slit to outer ends of the side fold lines and further having fold lines extending from the outer ends of said side fold lines and defining triangular areas and tabs which overlap and function as an inclined end wall and an additional attaching element, reinforcing member having the shape of the predetermined character and to which the character is secured by the attaching elements, and suspending tabs on said reinforcing member formed by partially cutting out areas from said reinforcing member.

2. The structure of claim 1 wherein portions of the said flanges are serrated.

3. A device of the kind described produced from a foldable paper blank and comprising inclined joined side walls and inturned attaching elements conforming to the shape of a predetermined character, triangular end walls produced by folding extensions of the side walls into overlapping relation, a reinforcing member having the shape of the predetermined character and to which the preformed character is secured, and suspending means carried by said reinforcing member.

CHARLES A. DINLOCKER.
